UNITED STATES PATENT OFFICE.

WASHINGTON I. SCHRYVER, OF PROPHETSTOWN, ILLINOIS.

NAPKIN-HOLDER.

SPECIFICATION forming part of Letters Patent No. 629,212, dated July 18, 1899.

Application filed November 14, 1898. Serial No. 696,439. (No model.)

To all whom it may concern:

Be it known that I, WASHINGTON I. SCHRYVER, a citizen of the United States, residing at Prophetstown, in the county of Whiteside and State of Illinois, have invented a new and useful Napkin-Holder, of which the following is a specification.

This invention relates to clasps, and more particularly to that type of clasps which are designed to be used as napkin-holders.

The object of the invention is to provide such a device which may be engaged upon the napkin at one end and clasped upon some portion of the clothing at its other end and suspend the napkin in a convenient and effective manner.

To this end the invention consists in the combination of parts, as will be hereinafter more fully described, and particularly pointed out in the claim.

In the drawings, Figure 1 is a perspective view of the device. Fig. 2 is a longitudinal sectional view thereof. Fig. 3 is a detail perspective view of the independent clasp.

Corresponding parts are denoted by like reference characters in all the figures of the drawings.

Referring to the accompanying drawings, 1 designates a spring-clasp having the jaws 2 and 3 connected together on a pivot-pin 4 and provided with a tension-spring 5, coiled about the pivot-pin and engaging the jaws with its opposite ends to normally hold the clasp closed in the usual manner. The present invention consists in applying to this spring-clasp another independent clasp, which will be designated the "napkin-clasp." This latter clasp is formed from a single length of metal bent intermediate its ends to form an eye 6 and a pair of jaws 7. The ends of these jaws are each preferably enlarged and slightly concaved, as shown at 8, to more firmly engage the napkin and are provided with a longitudinal slot 9 in the body of the jaw. These slots are adapted to be alined, and a double-headed button 10 is slidably mounted in the combined slots, with the heads engaging the opposite outside faces of the jaws, whereby the button may be moved longitudinally in the slot to clamp the jaws together upon the napkin. This napkin-clasp is connected to the spring-clasp by engaging the eye 6 about

the spring and pivot-pin of the spring-clasp, whereby the two clasps are pivoted or hinged together and capable of a limited sidewise movement. The jaws of the napkin-clasp extend outward between and beyond the thumb portions of the clasp 1, and thereby do not interfere with the latter and may be used independently thereof.

In the application of this device the napkin is placed between the jaws of the napkin-clasp, and the latter is clamped thereon by sliding the button 10 toward the free ends of the clasp, and then the spring-clasp is clamped upon some portion of the clothing of the person. The spring-clasp is preferably engaged upon the clothing, as it is more readily operated. However, either clasp may be used for either purpose, as desired. It will be noted that the napkin-clasp extends at one side only of the pivotal connection between the two clasps and is located between the divergent thumb portions of the spring-clasp, whereby the napkin-clasp does not interfere with the operation of the spring-clasp. This combination of the two clasps permits of either being operated independently of the other and provides a simple and convenient form of clasp for the purpose set forth.

Changes in the form, proportion, and minor details may be made without departing from the spirit and scope or sacrificing any of the advantages of the improvements.

Having thus described the invention, what is claimed is—

A device of the class described, comprising a pair of independent clasp members having a common pivotal connection, one of the clasps extending at one side only of the pivotal connection, and located between the thumb-pieces of the other clasp and in the same plane therewith, the first-mentioned clasp having its jaws located beyond the free ends of the thumb-pieces of the other clasp, substantially as and for the purpose set forth.

In testimony that I claim the foregoing as my own I have hereto affixed my signature in the presence of two witnesses.

WASHINGTON I. SCHRYVER.
